UNITED STATES PATENT OFFICE.

CHARLES T. FISHER, OF BATAVIA, NEW YORK, ASSIGNOR TO E. N. ROWELL CO., INC.,
OF BATAVIA, NEW YORK, A CORPORATION OF NEW YORK.

CABINET.

Application filed December 30, 1924. Serial No. 758,826.

My invention relates to cabinets and has for its object to provide a cabinet of novel construction and comprising one or more compartments provided with supporting means for rotatably carrying a web of material in the form of a roll and for maintaining the peripheral surface of said roll in engagement with a cutting device, in a simple and efficient manner. The invention more particularly contemplates the provision of a label cabinet adapted to contain rolls of labels mounted in individual compartments in a novel manner so as to have the peripheral surfaces of the rolls held in physical engagement with a cooperating cutting device, to enable individual labels to be separated from the web at will. Other more specific objects will appear from the description hereinafter and the features of novelty will be pointed out in the claims.

In the accompanying drawings, which illustrate an example of the invention without defining its limits, Fig. 1 is a front elevation of the invention embodied in a label cabinet; Fig. 2 is a plan view of one of the sections of said cabinet; Fig. 3 is a sectional elevation on the line 3—3 of Fig. 1; Fig. 4 is an end elevation of the cabinet; Fig. 5 is a detail section on the line 5—5 of Fig. 2; Fig. 6 is a perspective view of one form of the supporting means; Fig. 7 is a perspective view of a sleeve upon which the roll of material or labels is mounted; Fig. 8 is a rear view of one of the cabinet sections partly broken away and in section; Fig. 9 is a detail section on the line 9—9 of Fig. 8 and Figs. 10 and 11 are perspective views showing another form of supporting means included in the construction.

The cabinet in all of its forms comprises one or more compartments, a suitable cutting device or devices operatively combined with said compartment or compartments and supporting means for rotatably carrying a web of material in the form of a roll and for maintaining the peripheral surface of said roll in physical engagement with said cutting device under pressure to enable the web to be torn across at will and at predetermined points. Because of the fact that the invention is particularly adapted for use in connection with labels, I have shown the same in the form of a label cabinet. It will be understood that this is only an example and that the limits of the invention are not intended to be defined thereby.

As shown in the drawings, the cabinet comprises a base 15 from the opposite ends of which upright rods 16 project as shown in Figs. 1 and 4. If the base 15 is constructed of wood or similar material, it may be provided upon its upper surface with a facing of sheet metal 17 or its equivalent. A horizontal partition 18 of sheet metal or the like is mounted at intermediate points upon the rods or posts 16 and a similar sheet metal member 19 is mounted upon the upper ends of said posts and is secured in place, for instance, by means of knobs or the like 20, screwthreaded upon the ends of said posts which, in such case, are screwthreaded to receive the same. With this arrangement, the supporting means is divided into upper and lower chambers which may be counterparts of each other and each of which is adapted to removably receive a section of the cabinet. For the purpose of facilitating the placing of the cabinet sections in position on the support and their withdrawal therefrom, side members 21 may be provided as indicated in Fig. 4 which act as guides to guide the sections in their movements into and out of the chambers of the supporting means. To restrict the inward movements of the sections, strips 22 may extend lengthwise of the supporting means at the proper points as indicated in Fig. 3. The cabinet sections in the illustrated example comprise end members 23 dimensioned and shaped to fit into the upper and lower chambers of the supporting means and connected at the rear by means of upright members 24; in the preferred arrangement the latter are of relatively less height than the end members 23 and terminate at a distance below the upper edges thereof, as shown in Fig. 3. Members 23, 24, and 25 may be considered as forming the frame of each compartment. At the front, the end members are connected by means of members 25 extending downwardly from the upper edges of said end members and terminating at a distance above the lower edges; the members 25 in the example illustrated are bevelled at their lower edges to provide cutting devices 26 extending lengthwise of the cabinet sections. In addition,

the members 25 may be provided upon their front faces with devices 27 adapted to removably receive indicating sheets 28 whereby the contents of the cabinet compartments to be described hereinafter are visibly designated. Each cabinet section is divided into a plurality of compartments by means of transverse partitions 29 which preferably have their upper edges inclined downwardly from the top of the sections to the upper edges of the rear members 24, as shown in Fig. 3. Each of the compartments includes a supporting means for rotatably carrying the web of material, the character of the supporting means depending somewhat on the surface width of the web of material to be contained in the particular compartments. In any case, said supporting means is constructed in such a manner that it will maintain the surface of the roll of material in engagement with the cutting device, under gravitational pressure augmented by means of a resilient pressure developed through the medium of springs to be referred to more fully hereinafter. As shown in Figs. 3, 5, and 6, the supporting means comprises a journal 30 rotatably mounted upon a supporting rod 31 extending transversely between the walls 29 of each compartment and carrying a depending member 32 which, in addition to its other functions, constitutes a weight whereby the required pressure upon the roll of material is created. A rod 32^a projects from the member 32 in parallel relation to the journal 30 and at a distance therefrom and is adapted to rotatably receive the sleeve 33 on which the web of material in the form of a roll or more specifically the roll of labels 34 is mounted. In the preferred arrangement, the journal is recessed at its intermediate portion to provide a shoulder 30^a located beneath the rod 31 in the assembled condition of the device and in which one end of a flat spring 35 is permanently secured. The other end of the flat spring 35 is preferably provided with a circular abutment 36 or is otherwise constructed to eliminate friction as will appear more fully hereinafter. It will be understood that each of the compartments *a* is provided with a supporting means of the kind described and illustrated in Figs. 3, 5, and 6. If the webs of material or, in other words, the rolls of labels are relatively narrow in width, as indicated for instance in the compartments *b*, the supporting means, in addition to the parts so far described, may include an additional member 37 mounted upon the rod 32^a in spaced relation to the member 32 and provided with a recess 38 adapted to fit the journal 30 as shown in Figs. 9 and 10. For the purpose of maintaining the member 37 in the intended spaced relation to the member 31, a spacing block 39 may be located between said mem-

bers and may be permanently fixed upon the member 37. With the arrangement described and shown in Figs. 9 and 10 the free length of the rod 32^a is reduced to accommodate the relatively narrower rolls of material 34^a, as shown in Figs. 1, 8, and 9.

In the assembled condition of the cabinet, the rolls of material, or in other words the rolls of labels 34, are rotatably mounted upon the rods 32^a between the members 32 and the partitions 29; similarly the rolls of material or labels 34^a are rotatably mounted in the compartments *b* in surface engagement with the members 37 and the opposed surfaces of the partitions 29. The springs 35 are flexed, as shown in Figs. 3 and 9 and have their free ends 36 in engagement with the inner surfaces of the members 24. With this arrangement the peripheral surfaces of the rolls 34 and 34^a are held against the cutting device 26 under pressure developed by the weight of the members 32 alone or of the combined members 32 and 37; which pressure is augmented by the action of the springs 35 which at all times tends to force said peripheral surfaces against and into contact with the cutting devices 26. It will be understood that the relatively lighter rolls 34^a are held against the cutting devices 26 under a greater pressure than are the relatively wider and heavier rolls 34 so that the same degree of efficiency is secured in the device regardless of the physical characteristics of the roll of material itself.

As shown in Figs. 3 and 9, the free ends *c* of the rolls 34 and 34^a project more or less beneath the cutting device 26; if, for any reason, this should not be the case, the said free ends *c* may be brought into readily accessible positions by simply rotating the rolls 34 or 34^a through the medium of the finger inserted into the spaces beneath the aforesaid cutting devices. When it is desired to procure a portion of a predetermined web or, in the illustrated example, when a given label is desired, the free end *c* of the particular roll 34 or 34^a is grasped and the web of material or labels is withdrawn from said roll and beneath the cutting device 26 until the desired dividing line has been reached. If unintentionally or otherwise the web is withdrawn further than desired, it may be rewound upon the roll to the extent necessary to return the predetermined dividing line into registry with the cutting device 26 by simply inserting the finger into one of the aforesaid spaces beneath the particular cutting device and then manipulating the roll as required. As a matter of fact, these spaces make it easily possible to manipulate the rolls in any manner which may be necessary or desired. After the web has been withdrawn to the desired extent, the projecting portion of the web or, in other words, the label, is then

separated from said web by tearing it across the particular cutting device 26. It will be noted by reference to Fig. 5 that even when the roll of material has been completely removed from a given compartment and only the empty sleeve 33 remains upon the rod 32^a, the action of the device is such that the sleeve itself is pressed against the particular cutting device 26. The rolls of material or in other words the rolls of labels are thus efficiently maintained in cooperative relation with the cutting device 26 at all times, regardless of how much of the rolls has been removed or how little of said rolls remains upon the sleeves 33. When it is desired to replenish a compartment or compartments, the particular section in which said compartment or compartments is or are located is withdrawn from the supporting means so as to be completely disconnected therefrom and thereby render the compartments thereof easily accessible, as shown in Figs. 2, 5, 8, and 9. In this condition, the springs 35 may be disconnected from the rear member 24 and shifted to the position shown by dotted lines in Fig. 5 in which the member 32 and in some cases the members 32 and 37 of a given supporting means occupy the position shown also by dotted lines in said Fig. 5. In this position, the rod 32^a is located outside of the particular compartment and in a position to permit a new roll of material or of labels to be readily placed in position thereon. After this has been done, the parts may be returned to their normal positions within the particular compartments and the springs 35 again flexed to the positions shown in Figs. 5 and 9 in which the free ends of said springs are again in engagement with the rear member 24. The invention provides an efficient cabinet for containing one or a plurality of webs of material in the form of a roll or rolls supported in such a manner that predetermined sections or portions of said roll of material may be readily removed therefrom at will. The cabinet is particularly adapted for use in connection with labels such as are used by druggists and may be constructed so as to present a highly ornamental appearance. 50 The labels are at all times maintained in positions of ready accessibility and the devices may be replenished as necessary without difficulty. While the cabinet is specially adapted for use in connection with labels, 55 it obviously is adapted for use in other fields. Various changes in the specific forms shown and described may be made within the scope of the claims without departing from the spirit of my invention. 60

I claim:

1. A cabinet comprising a frame, a cutting device fixed to said frame, a weighted member pivotally suspended from said frame and adapted to support a roll of material in 65 rotatable relation, whereby the effect of the weight of the roll and of said member is to hold said roll in contact with said cutting device, and a spring fixed to said weighted member and slidably engaging said frame 70 for urging said roll toward said cutting device.
2. A cabinet comprising a frame, a cutting device fixed thereto, a weighted member pivoted to said frame and adapted to support a roll of material in rotatable relation, and a spring having one of its ends fixed to said weighted member and its other end slidable with respect to said frame and adapted to urge said roll into engagement 75 80 with said cutting device.
3. A cabinet comprising a frame, a cutting device fixed to said frame, a weighted member pivotally suspended from said frame, a rod fixed to and projecting from 85 said weighted member and adapted to support a roll of material in rotatable relation, said rod having its free end normally positioned adjacent a part of said frame, said weighted member being adapted to swing 90 upwardly to a loading position, and a spring fixed to said weighted member and bearing against said frame to urge the weighed member toward said cutting device.

In testimony whereof I have hereunto set 95 my hand.

CHARLES T. FISHER.
